UNITED STATES PATENT OFFICE.

FREEMAN D. MASON, OF AKRON, OHIO, ASSIGNOR TO THE BRIDGEWATER MACHINE COMPANY, OF AKRON, OHIO, A CORPORATION OF OHIO.

TRIMMER FOR STRIP MATERIAL.

Application filed December 22, 1925. Serial No. 76,988.

This invention relates to trimmers for use on strip material such as rubber weather strip, tire beads or the like, or other strip material having rough or uneven edges or fins due to the overflow occasioned during the vulcanizing of the articles.

It is the object of the invention to improve upon existing machines for doing this work, one purpose of the invention being to provide an improved driving means for operating both the trimming units of apparatus.

Another object of the invention is to provide an improved mounting for the co-operating trimmers whereby the cutters co-operate and the cutting is performed only at one point, thus insuring a neat and accurate cut and providing clearance between the trimmers for the stock to pass therefrom after the cutting operation.

Another object is to provide an improved mounting for a movable trimmer unit whereby it will be readily removable to facilitate sharpening or replacements of cutters, re-pairing, etc.

Another object is to provide an improved adjustment on one trimmer knife to position it properly with respect to the cooperating knife.

The foregoing and other objects are obtained by the construction illustrated in the accompanying drawings and described below. It is to be understood that the invention is not limited to the specific form thereof shown and described.

Of the accompanying drawings, Figure 1 is a plan of a trimmer embodying the invention, and shown as adapted for trimming beads;

Figure 2 is a front elevation thereof;

Figure 3 is a side elevation thereof;

Figure 4 is a detail of the split drive shaft;

Figure 5 is a detail plan of the trimmer knives and their mounts;

Figure 6 is a detail front elevation thereof, partly in section;

Figure 7 is a detail side elevation thereof;

Figure 8 is a detail front elevation of the trimmers, partly in section, illustrating them as adapted for operation on rubber weather strips.

Referring to the drawings, 10 represents

a support or base plate having thereon a motor 11 on the shaft of which is a pinion 12 meshing with a gear 13 on a drive shaft 14. Shaft 14 is journaled in a fixed bracket 15 and a movable bracket 16 and is held against longitudinal movement in its bearings by collars 17 adjustably secured thereon on one side of each of brackets 15 and 16. Driving gears 18, 18 are secured on the shaft on the other sides of each of said brackets 15 and 16.

In order to permit movement of bracket 16 relative to bracket 15, shaft 14 is adjustable as to length. For this purpose, the shaft is split into two parts, 14^a and 14^b, adapted to telescope into a sleeve 19 and having cooperating semi-cylindrical tongues 14^c and 14^d of considerable length to provide an adjustable driving connection therebetween, the sleeve 19 being adapted to be secured over the connection by means of a set screw 20.

The bracket 16 is secured to the base 10 by means of bolts 21, 21 engaged through slots 22, 22 therein. When the bolts are removed, the unit supported by and including bracket 16 is readily removable from the base 10 for replacement and repairs. Adjustment of bracket 16 toward and from bracket 15 may be accomplished by means of a screw 23 threaded therein, journaled in a bracket 24 on base 10 and operable by a hand wheel 25.

Each bracket 15 and 16 has journaled therein a shaft 26, aligned with one another. Each shaft carries a combined material supporting and lower shearing knife 27 and is driven by a gear 28 meshed with a pinion 18 on drive shaft 14. Each bracket 15 and 16 also has journaled thereon a shaft 29 offset vertically from shaft 26 (Figure 3). These shafts are not placed in alignment but are directed at a slight angle horizontally with respect to each other and to the shaft 26 (Figures 3 to 8) so that the shafts having shearing knives 30 thereon which, due to the vertical offset relation and the angularity of its mounting with respect to the cooperating knives 27, are adapted to engage the knives 27 at one point only, indicated at 31, at the point where the knives overlap (Figure 7).

By this arrangement a shearing action is provided and clearance is obtained between portions of the knives to the rear of the

point of cutting whereby the already cut edges of the strip material will not be further engaged by the knives beyond the point of cutting to affect the edges thereof in any way. Each shaft 29 has thereon a drive gear 32 meshed with a gear 28 whereby the knives 30 will be driven reversely from knives 27. Each knife 30 is adjustable into proper relation with a knife 27 by so mounting each shaft so that it is shiftable a slight distance longitudinally in its bearing, the adjustment being fixed by a knurled nut 33 thereon which bears against one end of the bearing. Each nut 33 has a set screw 33^a therein for securing it in adjusted positions.

To hold the material to be trimmed in proper relation to the knives 27 and 30, there is provided a pressure roller, such as 35 or 36, shaped on its periphery to fit the upper surface of the material to be trimmed. The roller is adapted to pass down between knives 30 to hold the material onto knives 27. Rollers 35 or 36 are replaceably mounted for rotation on an arm 37 carrying a spindle 38 for receiving either roller and secured therein so as to be adjustable longitudinally of the machine by means of a thumb screw 39 to properly fit between knives 30. Arm 37 is preferably pivoted onto an extension bracket 40 on the top of bracket 15 and the pressure rollers 35 or 36 may be releasably held thereon by means of a hand nut 41. Pressure on rollers 35 or 36 may be secured in any suitable manner, an extension 42 on arm 37 and carrying an adjustable weight 42^a being here shown. Arm 37 may be swung upwardly to facilitate insertion of the material into the machine and a projection 43 is provided thereon which is engaged in an arcuate slot 44 in bracket 40, which slot terminates in a shoulder at 45 adapted to hold the pressure rollers 35 or 36 and arm 37 in the dotted line position shown in Figure 3.

A strip guiding device is shown in Figures 1 and 3. This device comprises spaced apart vertically disposed rollers 46, 46 shaped substantially as inverted cones and relatively adjustable transversely of the machine in front of the knives in a bracket 47 mounted on base 10.

In the use of the machine to trim beads which are usually endless, the machine is set up and adjusted as shown in Figures 1 to 7, pressure roller 35 being used. The bead indicated in dotted lines is circumferentially driven through the machine by action of knives 27 and roller 35 thereon and is progressively trimmed at the edges as clearly shown in Figure 6. In Figure 8 the machine is shown performing a similar operation on weather strip material, the brackets 15 and 16 being adjusted closer together and pressure roller 36 being employed. The adjust-

ment and replacement of the parts for various purposes will be readily understood from the description of the construction of the machine.

Modifications of the invention other than those disclosed herein may be resorted to without departing from the spirit thereof or the scope of the appended claims.

What is claimed is:

1. A machine of the class described, comprising a normally fixed bracket, a pair of cooperating rotary trimming knives mounted thereon, a shiftable bracket, a pair of cooperating rotary trimming knives thereon arranged in alignment with corresponding knives of the first pair, and means for simultaneously driving both pairs of knives, comprising a drive shaft journaled in said brackets, said shaft being transversely split and having a sleeve secured thereon over the split, the split ends having relatively adjustable interlocking driving portions thereon, a gear on each section, and gears connected to each of said knives on each bracket and in mesh with each other, one of said last named gears on each bracket meshing with a gear on a shaft section.

2. A machine of the class described, comprising a normally fixed bracket, a pair of cooperating rotary trimming knives mounted thereon, a shiftable bracket, a pair of cooperating rotary trimming knives thereon arranged in alignment with corresponding knives of the first pair, and means for simultaneously driving both pairs of knives, comprising gears connected to each of said knives on each bracket and in mesh with each other, a drive shaft, and gears on said drive shaft, one being adjustable with said movable bracket, and each of said last-named gears being meshed with a knife-driving gear.

3. A machine of the class described, comprising a normally fixed bracket, a pair of cooperating rotary trimming knives mounted thereon, a shiftable bracket, said shiftable bracket having slots therein and bolts extending through said slots into the base for guiding the bracket whereby said bracket may be readily removed from the base, means for moving the shiftable bracket, a pair of cooperating rotary trimming knives on the shiftable bracket arranged in alignment with corresponding knives of the first pair, and means for simultaneously driving both pairs of knives.

4. A machine of the class described, comprising a normally fixed bracket, a pair of cooperating rotary trimming knives mounted thereon, said knives being arranged in offset relationship and the axis of one of said knives being at a slight angle with respect to the other whereby the knives will engage substantially at one point only, a shiftable bracket, a similarly mounted pair

of cooperating rotary trimming knives thereon arranged in alignment with corresponding knives of the first pair, and means for simultaneously driving both pairs of knives.

5. A machine of the class described, comprising a normally fixed bracket, a pair of cooperating rotary trimming knives mounted thereon, the axis of one of said knives being at a slight angle with respect to the other whereby the knives will engage substantially at one point only, a shiftable bracket, a similarly mounted pair of cooperating rotary trimming knives thereon arranged in alignment with corresponding

knives of the first pair, and means for simultaneously driving both pairs of knives.

6. Apparatus of the class described, cooperating rotary disc knives, shafts on which said knives are mounted, bearings for 20 said shafts, one of said shafts being longitudinally adjustable a slight distance in its bearing whereby one knife may be adjusted into shearing relationship with the other, and means for securing said shaft in adjusted positions comprising a single nut threaded thereon between the knife and the adjacent end of the bearing and operable against said end of the bearing. 25

FREEMAN D. MASON.
